United States Patent Office

Des. 193,841
Patented Oct. 16, 1962

193,841

WHEEL COVER

Richard N. Esajian, 5465 E. Pitt Ave., Fresno, Calif.

Filed Oct. 6, 1961, Ser. No. 66,989

Term of patent 14 years

(Cl. D14—30)

FIG. 1 is a perspective view of a wheel cover showing my new design.

FIG. 2 is a top plan view thereof; and

FIG. 3 is a side elevational view thereof.

I claim:

The ornamental design for a wheel cover, as shown.
